No. 844,232.

PATENTED FEB. 12, 1907.

F. BAKER.
STEERING MECHANISM.
APPLICATION FILED JULY 18, 1906.

UNITED STATES PATENT OFFICE.

FRANK BAKER, OF SYRACUSE, NEW YORK, ASSIGNOR TO BAKER GEAR COMPANY, OF HOMER, NEW YORK, A CORPORATION OF NEW YORK.

STEERING MECHANISM.

No. 844,232.

Specification of Letters Patent.

Patented Feb. 12, 1907.

Application filed July 18, 1905. Serial No. 270,202.

To all whom it may concern:

Be it known that I, FRANK BAKER, of Syracuse, in the county of Onondaga, in the State of New York, have invented new and useful 5 Improvements in Steering Mechanism, of which the following, taken in connection with the accompanying drawings, is a full, clear, and exact description.

This invention relates to improvements in 10 steering mechanism for automobiles, and refers more particularly to the means for oscillating the axle-studs for the front wheels.

The primary object is to produce a maximum degree of oscillation of the front axle- 15 studs with a minimum movement of the hand-lever.

Another object is to locate the steering- 20 lever at the extreme outside of the box or body of the vehicle and to mount it in such manner that it may be moved back and forth along the side of the body in the operation of 25 steering, so as to afford as much available space in the front of the machine, or rather in front of the seat, as possible.

A further object is to relieve the hand- 30 lever and hand of the operator from excessive jar incidental to the engagement of the wheels with obstructions of the road and to render the steering action as easy as possible.

A still further object is to inclose the steering-gears in a substantially dust-proof case composed of sections, one of which supports 35 one of the gears and is adjustable upon the other section to take up wear.

Another specific object is to provide a simple adjusting means for taking up the end-thrust wear for the steering-rod and to utilize 40 this same means to lock the end-thrust step in its adjusted position.

Other objects and uses relating to the specific construction of different parts of steering mechanism will be brought out in the following description.

In the drawings, Figure 1 is a top plan of 45 my improved steering mechanism operatively connected to the swinging axle-stubs of the steering-wheel. Fig. 2 is an enlarged vertical sectional view, partly broken away, of the essential features of my improved steering mechanism. Fig. 3 is a top plan of the lower gear-case section seen in Fig. 2, showing one of the gears as mounted therein, and

also showing the steering-rod in section with its gear keyed thereto. Figs. 4 and 5 are sectional views taken, respectively, on line 55 44, Fig. 3, and 55, Fig. 4.

In order to demonstrate the practicability of my invention, I have shown the front axle A of an automobile as provided with horizontally-swinging axle-studs a, having crank- 60 arms a' projecting rearwardly therefrom and pivotally connected to the ends of a connecting-bar B, one of said crank-arms being connected to one end of a draw-bar C, which extends transversely and diagonally across the 65 under side of the machine. The other end of this rod is connected in a manner herein-after described to the parts of the steering mechanism which form the subject-matter of my present invention.

As best seen in Figs. 2 to 5, inclusive, this invention consists, essentially, of a steering-post 1, having its lower end keyed or otherwise secured to a worm 2, meshing with a worm-gear 3, to which is secured a depending crank-arm 4, the latter being connected by knuckle-sections 5 and 6 to the draw-rod C. The upper end of this steering-post 1 is provided with a gear 7, which is keyed or otherwise fixed to said post and meshes with 80 a toothed curved rack 8 upon a hand-lever 9, said lever being fulcrumed at 10 at a point below the rack 8.

As best seen in Fig. 1, the steering-post and its rotating means, as the rack 8 and 85 lever 9, are located in close proximity to and preferably just outside of the side of the box, as D, indicated by dotted lines in said figure, the lever 9 extending upwardly within easy reaching distance from the seat (not shown) 90 of the vehicle.

I have thus far described the general construction of my improved steering mechanism, and it will be observed that the lever is fulcrumed to swing back and forth substantially parallel with the body of the vehicle, as indicated by the dotted line D, and that when the lever is thus oscillated back and forth rotary motion is imparted to the upright steering-post 1 through the medium of the 100 rack 8 and pinion 7, and simultaneously with this movement the crank-arm 4 is oscillated back and forth in the direction of extension of the draw-rod C, through the medium of the

gears 2 and 3, thereby reciprocating the rod C and oscillating the axle a, to which it is connected, similar oscillatory movement being transmitted to the other axle-stub a by means of the connecting-rod B.

In order that the gears 2 and 3 may be protected from the elements, and particularly against the entrance of dust, I inclose them within a special form of dust-proof case or housing, consisting in this instance of a lower case-section 11 and an upper case-section 12, which meet slightly below their horizontal center and are clamped together by suitable fastening means, as bolts 13. This casing or housing for the gears 2 and 3 may be supported in any desired manner upon the body or frame of the machine near one side, and in view of the fact that the manner of mounting will depend largely upon the construction of the machine to which the steering mechanism is applied it is believed to be unnecessary to enter into a description of any particular fastening means. I have, however, shown the upper section 12 as provided with a projecting flange or web 14, by which the device may be readily attached to some part of the body or frame of the machine, as a hanger or bracket 15. This upper case-section 12 caps over the gears 2 and 3 and is provided with an upwardly-projecting hollow boss 16, which receives a brass or bronze bushing 17 and an upwardly-projecting hub 18 of the worm 2, said hub being secured by a key 19 to the post 1 to rotate therewith and is journaled in the brass bushing 17.

The hub of the worm-gear 2 is inserted from the under side into the bushing 17 and hub 16 before the case-sections 11 and 12 are brought together, and in order to reduce the friction incidental to the upward end-thrust of the gear 2 and at the same time to afford a broad bearing to prevent undue cramping of the gear and steering-post I provide the upper face of the gear 2 with an annular groove or ball-race 21, surrounding the inner end of the hub 18 for receiving antifriction-balls 22, which bear against the under side of a hardened washer 23, the latter being held against rotation by a pin 24, entering an aperture in the under side of the case-section 12, against which the washer 23 also bears.

By keying the steering-post 1 to the worm 2 the latter constitutes a unitary part of the steering-post, and in order to prevent lost motion or undue endwise movement the lower face of the steering-post, or rather of the worm-gear 2, is stepped in a vertically-adjustable bearing 25, which in this instance consists of a hard metal disk underlying the lower face of the worm-gear 2 and having a central upwardly-projecting boss 26 entering a central aperture in the worm-gear 2.

Rigidly secured to or integral with the plate 25 is a depending screw-threaded stem

27, having an angular lower end 28 for receiving a wrench or other tool, by which the step or plate 25 may be adjusted endwise. This screw-threaded stem 27 projects through an elongated slot 29 in the bottom of the lower case-section 11, and engages inner and outer jam-nuts 30 and 31, by which the plate or disk 25 is firmly locked to the lower section, suitable washers 32 being interposed between the nuts 30 and 31 and adjacent faces of the bottom of the case-section 11 to bridge across the slot 29.

The upper nut 30 and adjacent washer 32 are locked against rotation by a pin 33, which enters an aperture in the bottom of the case-section 11 at one side of the screw 27, the object of this being to permit the vertical adjustment of the step or disk 25, and at the same time allow the lower case-section 11 to be adjusted transversely of the axis of the screw 27 and steering-post 1.

The lower face of the worm-gear 2 is also provided with an annular recess or ball-race 34, which is covered by the disk 25 and receives antifriction-balls 35, bearing upon the upper face of the disk 25.

When it is desired to adjust the plate 25 endwise, or to take up the wear of the end-thrust bearing for the steering-rod 1, it is simply necessary to loosen the jam-nuts 31 and then rotate the screw 27 until the end-thrust bearings are sufficiently tight and still capable of revolving easily, whereupon the jam-nut 31 is again tightened to hold the step 26 against endwise or rotary movement, it being understood that the broad bearings upon which the worm-gear 2 rests prevents undue cramping or torsional strains of the gear 2.

The gear 3 is keyed to a hub 35 of the crank-arm 4 and fits with an easy running fit within the case-sections 11 and 12, so that its opposite end faces bear against annular bearings 36 on the inner faces of the sections 11 and 12, which surround the hub 35, said end bearings being comparatively broad and prevent endwise movement of the gear 3. This gear 3 and the hub 35 of the crank-arm 4 are supported wholly by the lower section 11, which is provided with a pair of opposed upwardly-projecting ears 37 and 37', receiving between them the adjacent portion of the upper case-section 12, the ear 37 being provided with a central threaded aperture 38 for receiving the threaded end of a taper-screw 39, which latter extends through a central aperture 40 in the ear 37' and is held against rotation by a set-screw 41. This tapering screw 39 passes through a similar tapered aperture in the hub 35 of the crank-arm 4 and may be readily adjusted endwise by a screw-driver or other tool upon loosening the set-screw 41 for the purpose of taking up any wear incidental to the oscilla-

tion or partial rotation of the hub 35 upon said screw, the set-screw 41 being retightened after such adjustment. It is now clear that the gear 3, which is keyed to the hub 5 of the crank-arm 4, revolves with said hub upon the fixed pivotal pin 39 and that said pivotal pin is supported wholly upon the ears 37 and 37' of the lower case-section 11.

The means for adjusting the lower case-section 11 consists of an adjusting-screw 42, which engages the threaded aperture 43 in a lug 44 on the end of the lower case-section 11 and has a reduced portion 45 journaled in a lug 46 on the adjacent end of the upper case-section 12, so that by rotating the screw 42 the lower case-section, carrying the gear 3 and crank-arm 4, may be adjusted to take up any wear between the gears 2 and 3, after which the screw is tightened by a jam-nut 47, it being understood that the slot 29 and similar slots 29' for the clamping-bolts 13 allows such adjustment. It is now clear that the backward and forward movement of the lever 9 rotates the steering-post 1 and its worm-gear 2 to transmit rocking motion to the gear 3 and crank-arm 4, by which the axle-stubs *a* are oscillated horizontally through the medium of the draw-rod C, which necessarily changes its angle during such reciprocal movement, while the gear-case is fixed and the crank-arm 4 therefore oscillates in the same plane. It therefore becomes necessary to provide a knuckle-joint between the rod C and crank-arm 4, such connection consisting of the knuckle-sections 5 and 6, the section 5 being pivoted at 5' to the lower end of the crank-arm 4 on a horizontal axis, while the section 6 is screwed onto the adjacent threaded end of the rod C and is pivotally connected by a vertical pivotal pin 6' to the adjacent end of the knuckle-section 5.

It will be seen upon reference to Fig. 5 that the portion of the upper section 12 of the gear-case inclosing the gear 3 overhangs the top and sides of the adjacent end of the hub 35 and crank-arm 4, forming a dust-proof joint with the ear 37' and that the lower portion of the ear 37' has a vertical opening through which the arm 4 projects and which is elongated transversely to allow ample space for the oscillation of the crank-arm 4.

The essential features of my invention consist in connecting the steering-axles to a gear-operated crank-arm, mounting the gear in a dust-proof case composed of sections, one of which is adjustable transversely of the axis of the steering-post for the purpose of taking up the wear between the gears, rotating the steering-post by means of a lever, rack, and pinion, the lever being located at one side of the vehicle-body, connecting the crank-arm to the draw-bar C by a knuckle-joint, next

mounting one of the gears upon the hub of a crank-arm upon a tapering pivotal pin to permit taking up of the wear incidental to the oscillation of said arm upon said pin.

What I claim—

1. In a steering mechanism, the combination with steering-axles and a connecting-rod between them, of a draw-bar connected to one of the axles, an oscillatory crank-arm connected to the draw-bar to reciprocate the latter, a gear-case in which one end of the crank-arm is mounted, a gear secured to the crank-arm, a worm meshing with the gear, both worm and gear being incased, an upright steering-post having one end journaled in the case and secured to the worm, a pinion on the upper end of the steering-post and a lever having a toothed rack engaged with the pinion, whereby the oscillation of the lever rocks the steering-post and oscillates the crank-arm through the medium of the gears. 85

2. In a steering mechanism, the combination of intermeshing worm-gears and an inclosing case in which said gears are mounted to rotate, a crank-arm secured to one of the gears, a steering-post secured to the other gear, a hand-lever, a toothed rack on the lever and a pinion on the steering-post meshing with the toothed rack. 90

3. In a steering mechanism, the combination with an upright rotary steering-post and means to rotate it, of a worm-gear secured to the post, a second gear meshing with the worm-gear, means for adjusting one of the gears radially relatively to the other gear to take up wear and a crank-arm secured to the second gear and connected to the steering-axes. 95

4. In a steering mechanism, the combination with steering-axles and means connecting them, of a draw-rod connected to one of the axles, a gear-case and intermeshing gears therein, a tapering pivotal pin secured to the gear-case and adjustable endwise, a crank-arm journaled on said pin and connected to the draw-bar, one of the gears being secured to the hub of the crank-arm, a steering-post journaled in the gear-case and secured to the other gear, and means to rotate the steering-post. 110

5. In a steering mechanism, an upright rotary steering-post having a worm at one end, a gear meshing with the worm, a gear-case inclosing the worm and gear and composed of sections, one of which is adjustable transversely of the axis of the steering-post, one of the gears being mounted upon the adjustable case-section, and means for clamping the case-sections together. 115

6. In a steering mechanism for automobiles, the combination of an upright rotary steering-post and operating means therefor, a worm secured to the lower end of the steering-post, and provided with end-thrust bear- 120 125

4
ing-faces, end-thrust bearings at opposite ends of the worm, one of which is adjustable endwise, a worm-gear meshing with the worm, means to adjust said gear to take up 5 the wear, a crank-arm secured to the gear and a draw-rod connected to the crank-arm and adapted to be connected to the steering-axles of the vehicle.

7. In steering mechanism for automobiles, 10 the combination with intermeshing steering-gears and an inclosing case therefor, said case being composed of sections, one of which is adjustable with relation to the other and receiving and supporting one of the gears.

15 8. In a steering mechanism for automobiles, a gear-case consisting of a fixed section and a movable section adjustable relative to the fixed section, a gear journaled in the fixed section and a second gear journaled in 20 the movable section and meshing with the first-named gear.

9. In a steering mechanism for automobiles, a gear-case consisting of a fixed section and a movable section, a steering-post and 25 worm secured thereto and journaled in the fixed section, a pivotal pin mounted on the

movable section, a crank-arm having a hub journaled on the pin and a gear keyed to said hub and meshing with the worm, in combination with means for adjusting the movable 30 section of the case.

10. In a steering mechanism for automobiles, a gear-case composed of upper and lower sections, one section being adjustable relatively to the other section, a steering-post rotatably mounted in the upper section and provided with a worm, a worm-gear journaled in the lower case-section and meshing with said worm, an end-thrust bearing axially adjustable in the lower case-section 35 and engaging the lower face of the worm, a crank-arm secured to the worm-gear, and a tapering screw passed through the crank-arm and worm-gear and secured to the lower case-section. 40

In witness whereof I have hereunto set my hand this 11th day of July, 1905.

FRANK BAKER.
